DENTAL ENGINE ATTACHMENT

Hyman Freedman, New York, N. Y., assignor of
one-half to Bertha Freedman, New York, N. Y.

Application June 7, 1943, Serial No. 489,901

9 Claims. (Cl. 32—23)

1

This invention relates to improvements in dental engines and has particular reference to a supporting means for the hand piece or dental tool.

Heretofore, it has been the common practice to provide a supporting hook on the extension arm of a dental engine from which hook the hand piece is suspended when not in use. In actual practice, a dentist, during an operation, has many occasions to replace the hand piece in its suspended position on the hook and often does so without observing whether the tool is secure thereon. As a consequence it is not uncommon for the tool to become accidentally detached and fall from its hook with considerable force and strike a patient with the possibility of serious injury. In fact, only recently, an accident of this nature happened and a drill attached to the hand piece penetrated a patient's skull, resulting in her death.

To minimize the possibility of such unfortunate accidents, it is proposed, by the present invention, to provide additional means supplementing the customary supporting hook which will effectively prevent the fore arm that carries the hand piece from falling in the event that said hand piece should become accidentally detached from said hook while in a suspended position thereon.

Accordingly, a feature of the invention is to provide means associated with the extension and fore arms of the dental apparatus and preferably arranged adjacent the pivotal connection between said arms, which means will become effective to retain the fore arm in the position it assumes when the hand piece is suspended on the supporting hook should said hand piece become accidentally detached from said hook.

A further and more specific feature is to mount a permanent magnet on one arm of the apparatus in such manner that said magnet will remain in magnetically opposed relation to another arm irrespective of any turning movement of the first named arm relative to said magnet.

The inventive idea involved is capable of receiving a variety of mechanical expressions some of which, for purposes of illustration, are shown in the accompanying drawing; but it is to be expressly understood that said drawing is used only for the purpose of facilitating the description of the invention as a whole and not to define the limits thereof, reference being had to the appended claims for this purpose.

In the drawing:

Fig. 1 is a fragmentary elevational view of a dental engine of conventional form, showing the present invention applied thereto.

Fig. 2 is an enlarged side elevation of the mag-

2

netic means for retaining the extension and fore arms in their inoperative positions.

Fig. 3 is a section on the line 3—3 of Fig. 2.

Fig. 4 is a section on the line 4—4 of Fig. 2.

Fig. 5 is a section on the line 5—5 of Fig. 2.

Fig. 6 is a view similar to Fig. 2, partly in section, showing a modified form of the invention, and

Fig. 7 is a section on the line 7—7 of Fig. 6.

Referring more particularly to the drawing, the numeral 10 indicates a portion of the engine arm of any conventional type of dental engine, which arm is provided at its outer end with the upper pulley 11 around which passes the usual drive belt 12 for the hand piece 13. The extension arm 14 has a universal pivotal connection at its upper end with the arm 10 and, at its lower end, has a similar connection with the lower end of the fore arm 15. An idler pulley 16 is also located at the lower ends of said arms and the belt 12 also engages around said pulley and then extends upwardly and around the pulley 17 at the upper end of the arm 15, and from thence to the drive pulley 18 on the hand piece 13. The upper end of the arm 15 has the usual universal connection with an arm 19 which carries said handpiece 13 and, when the latter is not in use, it is engaged with a supporting hook 20 attached to the extension arm 14 adjacent its upper end. The construction thus far described is well known in the art and therefore requires no further explanation.

In accordance with the present invention, means are provided for releasably retaining the arm 15 in its suspended or inoperative position shown in Fig. 1 in the event that the arm 19 should become accidentally detached from the hook 20, and thereby prevent said arm 15, together with the hand piece 13, from falling away from said hook. Said means is desirably positioned between and associated with the lower ends of the arms 14 and 15 and preferably takes the form of a permanent horse shoe magnet 21 supported on the arm 14 and a keeper 22 carried by the arm 15. As will be evident, said magnetic elements, when brought into proximity, will attract each other and the magnetic flux passing between the same will be sufficient to hold the arms 14 and 15 in their suspended or inoperative positions even though the arm 19 is disengaged from the hook 20.

In order to support the magnet 21 on the arm 14 so that said magnet will remain in opposed relation to the keeper 22 regardless of any axial turning movement of said arm, a casing 23 is provided for said magnet, which casing is made

of any suitable non-magnetic material such as brass. Said casing comprises side walls 24 between which the magnet is received and wherein it is secured by a rivet 25. One end of said casing terminates in opposed resilient clamping portions 26 which are engageable about the sleeve 27 in which the arm 14 is rotatable. Said sleeve extends upwardly from a rectangular member 28 upon which the lower ends of the clamping portions 26 rest and, in order to prevent any rotation of the casing while the arm 14 might be rotating in said sleeve, said clamping portions are provided with depending extensions 29 which engage opposed faces of the stationary portion 28.

The support for the keeper 22 is somewhat similar in construction to that of the magnet 21. Thus, as best shown in Fig. 5, said support comprises a member 30 having opposed clamping portions 31 which partially embrace a sleeve 32 carried by the upper end of a rectangular member 33, and extensions 34 on the lower ends of the clamping portions 31 engage opposed faces of the member 33 so that said support will not turn if the arm 15 is rotated. The keeper 22 is resiliently carried by the support 30 by means of two coil springs 35 interposed between and secured to said support and keeper, this construction enabling the keeper to at all times have flush engagement with the pole pieces of the magnet 21. Also, by providing a mounting of this character for the keeper and having the springs 35 of proper tension, it will be observed that as said keeper approaches the magnet toward the end of the movement of the fore arm to its inoperative position and before the hand piece is engaged with the hook 20, the magnet will become effective to attract said keeper and thus hold said fore arm in said position even if the hand piece should not be engaged with the hook.

In such construction it will be noted that as the forearm 15 is moved toward the extension arm 14, the keeper 22 will move forward into engagement with the permanent magnet 21 at an accelerated speed. Upon engagement of the keeper with the permanent magnet an audible sound or signal is heard which immediately indicates to the operator that the magnetic lock has been made effective. On the other hand, if the aforementioned arms, upon relative movement toward each other do not produce an audible sound or signal the operator is warned of the failure of the securing means to become effective.

In the form of the invention shown in Figs. 6 and 7, the magnet 36 is mounted on a support 37 which is of substantially the same construction as the member 23 and is carried on the sleeve 27 associated with the arm 14. However, instead of providing a keeper on the arm 15, the sleeve 38 in which said arm is rotatable is made of magnetic material and is directly engageable with the pole pieces 39 of the magnet 36 when the arms 14 and 15 are in their inoperative positions.

What is claimed is:

1. In a dental engine, pivotally connected extension and fore arms the latter of which has an infinite number of inoperative positions, one of said positions being adjacent said extension arm, members in which both said arms are axially rotatable, magnetic elements supported by said members in opposed relation to each other and disposed adjacent the pivotal connection between said arms, and means to retain said magnetic

elements in such relation irrespective of any rotary movement of either of said arms.

2. In a dental engine, pivotally connected extension and fore arms having an infinite number of inoperative positions, said fore arm having an inoperative position adjacent said extension arm, a member including a sleeve, in which one of said arms is axially rotatable, a removable casing positioned adjacent the pivotal connection between said arms and having clamping portions engageable with said sleeve said casing having means engaging said member to prevent rotation of said casing when said arm is rotated, and a magnet supported by said casing contiguous to said pivotal connection and operatively associated with the other of said arms to retain said fore arm in its inoperative position.

3. In a dental engine having a forearm, an extension arm, and means for mounting a tool on said forearm, primary locking means for supporting said forearm in a first locked position, and secondary locking means for supporting said forearm in a second locked position adjacent said first position, said secondary means including mechanism actuated by movement of the forearm to a point proximate either of said locked positions.

4. In a dental engine having a forearm, an extension arm, and means for mounting a hand tool on said forearm, primary means for supporting said forearm in a first position, and secondary means for supporting said forearm in a second position adjacent to and spaced from said first position, said secondary means comprising a member mounted on one of said arms, and a second member mounted on the other of said arms and actuated to connect with said first member upon movement of said second member to a point proximate said first member and before said other arm has reached said second position.

5. In a dental engine having a forearm, an extension arm, and means for mounting a hand tool on said forearm, primary means for supporting said forearm in a first position, and secondary means for supporting said forearm in a second position adjacent said first position, said secondary means comprising a fixed member mounted on one of said arms and a movable member mounted on the other of said arms adapted to connect with said fixed member upon movement of either of said members toward the other.

6. In a dental engine having a forearm, an extension arm and means for mounting a tool on said forearm, primary means for supporting said forearm in a first position, and secondary means for supporting said forearm in a second position adjacent said first position, said secondary means comprising a magnet fixedly mounted on one of said arms and a keeper bar resiliently mounted on the other of said arms, said keeper bar being actuated to connect with said magnet when one of said arms is moved to a point proximate said first position.

7. In a dental engine having a forearm having an infinite number of inoperative positions, an extension arm, and means for mounting a tool on said forearm, a first and second inoperative positions for said forearm, said second inoperative position being spaced from said first inoperative position, means for retaining said forearm in said first inoperative position, and means for retaining said forearm in said second inoperative position, said last means becoming effec-

tive as said forearm moves from said first inoperative position to said second inoperative position.

8. In a dental engine having a forearm having an infinite number of inoperative positions, an extension arm, and means for mounting a tool on said forearm, means pivotally connecting one end of each of said arms, said forearm having a first inoperative position and a second inoperative position adjacent said first position, and magnetic means disposed on at least one of said arms adjacent said pivotal connection for maintaining said forearm in said second position.

9. In a dental engine as described in claim 8, and means for supporting said forearm in its first inoperative position, said last means comprising a hook mounted on said extension arm, said hook being engageable by said tool mounting means.
